UNITED STATES PATENT OFFICE.

CHARLES W. STEVENS, OF ELIZABETH, NEW JERSEY.

MACHINE FOR FORMING HATS.

No. 843,638.

Specification of Letters Patent.

Patented Feb. 12, 1907.

Application filed August 17, 1904. Serial No. 221,156.

To all whom it may concern:

Be it known that I, CHARLES W. STEVENS, a citizen of the United States, residing at Elizabeth, Union county, New Jersey, have 5 invented certain new and useful Improvements in Machines for Forming Hats, of which the following is a full, clear, and exact description.

My invention relates to machines for forming hats.

The object of my invention is to provide mechanism of an improved form for compressing the crowns of the hats and for simplifying the formation of a more perfect 15 hat and making the operation more effective and quicker.

The invention is particularly adapted for use in machines for forming hats having bell-shaped crowns from blanks of felt or other 20 similar material which may be pressed into shape by dies.

The invention consists in improvements 25 the principles of which are illustrated in the accompanying two sheets of drawings.

Briefly, the invention may be said to comprise the employment of dies for shaping and 30 compressing the brim of the hat and then compressing and forming the crown, both operations being effected by pressure from the same source. The latter operation is effected 35 by a plurality of hinged members which have broad bearing-surfaces and overlap each other. The crown-forming dies are carried by a frame which may be provided with suitable means for raising and lowering the same 40 such as is commonly employed in presses of this general character. The upper brim-forming member is carried by the same frame, but may be disengaged, and is provided 45 with locking means, so as to obtain two distinct movements, one of the brim-forming die and the other of the crown-forming die, but both by continued action of the frame either on the downward forming movement or the upward releasing movement.

Figure 1 is a front view of those parts of a machine which are necessary for illustrating the improvements of my invention. Fig. 2 50 is a horizontal plan and section of the same on the plane of the line 2 2, Fig. 1. Fig. 3 is a vertical section of the dies, taken on a plane at right angles to the view shown in Fig. 1. Figs. 4 and 5 are detail views of the upper 55 crown-forming dies, the former being a bottom view and partial section on the plane of

the line 4 4 of Fig. 5 and the latter a side view. Fig. 6 is a detail plan view, on an enlarged scale, of one of the crown-forming members. Fig. 7 is a similar view of another. A plurality of each of these is provided and arranged alternately, as indicated in Fig. 4.

1 indicates the table or bed of the machine which carries the lower dies and is adapted 60 to sustain the pressure applied thereto in forming the hat.

2 are operating-rods which pass through suitable guides in the main bed of the machine and are movable vertically with relation thereto. Suitable means may be provided for raising and lowering these dies as may be desired, such as springs and foot-levers, as is common and well-known in the art of presses.

3 is a cross-frame carried by the rods 2 2, which in its turn supports the upper dies and crown-forming members, all of which are movable with relation to the lower dies.

My invention is particularly directed to 80 that class of machines which is employed for shaping a blank having a bell-shaped crown. The parts are shaped accordingly; but it will be obvious to those acquainted with the art 85 that the particular shape of hat illustrated is immaterial and that my invention is adapted to a wider field of utility.

4 indicates the lower die, which has a suitably-formed upper surface for giving to the brim of the hat the desired shape. This lower 90 die 4 carries or supports the members for giving the desired shape to the inside of the crown. As this crown is bell-shaped the lower crown-shaping members are preferably constructed of a plurality of parts suitably shaped. In 95 the form herein shown it is formed in four parts, three of which are illustrated and indicated by the references 5, 6, and 7. Of these 5 and 6 are preferably movable, so as to permit the hat to be taken out after the crown is 100 formed. As my invention, however, relates more particularly to the mechanism for producing the compression on the upper side of the blank, the description and illustration of these parts will be more in detail.

Fig. 1 illustrates the machine in position 105 ready for the insertion of a blank.

8 is the member for shaping the top of the crown.

9, 10, and 11 are rods carried by the cross-frame 3, which support the crown-top member 110 8. 12 is the upper brim-shaping member,

which is also carried by the rods 10 and 11, but provided with locking and releasing mechanism.

13 and 14 are brackets secured to the upper 5 brim-shaper 12 and having perforations through which the rods 10 and 11 slide.

15 and 16 are locking members pivoted to the brackets 13 and 14 and which are hook-like and adapted to coact with the rods 10 10 and 11 at the contracted portions 17 and 18, so that when the locking members are in the position indicated in Figs. 1 and 2 pressure may be applied to the upper brim-shaper 12 by means of the presser-rods 22.

19 is a connecting-rod between the two locking members 15 and 16.

The locking member 15 is provided, preferably, with a handle, so that it may be manually operated to lock or release the parts. Fig. 20 3 shows the locks released.

20 and 21 are side rods carried by the brim-shaper 12 and guided by the cross-frame 3.

22 and 23 are springs which are adapted to coact to press the upper brim-shaper 12 25 downward when the locking members 15 and 16 are released. The weight of the parts will tend to hold the upper brim-shaper in its proper position, but the springs are added to give additional pressure.

30 After the blank has been placed in the machine the cross-frame 3 is caused to descend, and thus pressure is applied to form the brim and hold it in position. The locking members 15 and 16 are then released by a 35 single movement of the handle member 15. Continued pressure on the rods 22 causes the crown-top member 8 to continue to descend and perform the operation of shaping the crown, the rods 10 and 11 sliding through the 40 brackets 13 and 14.

To form the bell-shaped crown, a plurality of side clamps are employed, which comprise the annular outer crown-shaping die. I prefer to use eight, four of each of two kinds arranged alternately with overlapping edges 45 and curved corners. Figs. 6 and 7 illustrate in plan view the two different forms, while Figs. 4 and 5 illustrate the arrangement on a smaller scale. These side clamps are designated by the numerals 24 and 25 and are movable toward and from each other. They are hinged to the top member 8 and when in the position shown in Fig. 1 hang vertically by gravity separated from each other. The 50 upper brim-shaper 12 is provided with a centrally-located opening, through which the lower crown-dies or block members 5, 6, and 7 cause the crown of the blank to be projected during the formation of the brim. The side 55 walls of this opening are formed sloping, as illustrated in Fig. 3, and the outer surfaces of the side clamping devices 24 and 25 are formed suitably to coact therewith, so that when the locking members 15 and 16 are released and the top member 8, together with

the clamps, descends the clamps will be forced inwardly toward each other into the position shown in Fig. 3.

The inner shaping-surfaces of the clamps are suitably curved or shaped to engage the outer sides of the blank and give the desired contour to the outside of the crown. The lower edges 26 and 27 of the clamps are suitably formed to give an annular depression in the hat between the bottom of the crown and the brim. This is shown particularly in Fig. 3, in which 28 indicates a section of the hat. Portions 24' and 25' of the clamp members 24 and 25 near the lower edges serve as outer shaping-surfaces which engage the hat material 28 in the annular depression just mentioned, and thus shape part of the brim. As before stated, the alternate clamping members overlap each other. The lower inner corners of the members 25 are preferably 85 rounded off, as indicated at 29 and 30, Fig. 7, while the members 24 have correspondingly-shaped recesses 29' and 30'. The lower inner corners of the shaping members 24 are also rounded adjacent to the lower edge 27 90 of the shaping member 25. This prevents the clamping members from pinching or catching the material of the hat when in operation, because they are in constant engagement or contact with one another during the 95 entire contracting period incidental to the shaping of the sides and the crown. The members 25 are preferably considerably 100 wider at their lower portions than at the top, so as to prevent them from getting jammed or wedged between the members 24 as they are brought into operation. The inner shaping-surfaces of the members 24 and 25 are inclined somewhat like the surface of the frustum of an inverted cone.

When the hat has been formed and the parts are in the position shown in Fig. 3, the operating presser-rods 22 are raised. This raises the cross-frame 3, carrying with it rods 9, 10, and 11 and the top crown-forming member 8, thus releasing the crown and permitting the clamps 24 and 25 to hang down vertically. The continued upward movement of the presser-rods 22 and the cross-frames 3 raises the upper brim-forming member 12 and releases the completely-formed hat.

The advantages of this construction will be apparent to those skilled in the art. It will also be apparent that my invention may be employed to form hats of many designs or shapes and sizes with flat, curved, or fluted brims and flat, concave, or convex tops.

What I claim is—

1. In a hat-forming machine, the combination of a supporting-bed, a cross-frame movable with relation thereto, lower brim and crown forming dies carried by said bed, upper crown-forming dies, an upper brim-forming die, means for supporting said crown-forming 125

130

dies from said cross-frame, means for supporting said brim-forming die from the supporting mean for said crown-forming dies, and locking and releasing means for causing said 5 brim-forming die to descend in advance of said crown-forming dies and permitting said crown-forming dies to descend after said brim-forming die.

2. A shaping-machine, including 10 segmental inner and outer dies, the segments of one of said dies being more than four in number and arranged in two sets movable toward and from each other, the segments of one set of said segments being substantially wider at 15 the lower edge than at the upper, and the segments of the other set being substantially wider at the upper edge than at the lower and constantly overlapping the segments of the first set at their free edges.

20 3. In a hat-forming machine, the combination of a cross-frame with operating-rods, an upper crown-forming die carried thereby, an upper brim-forming die and locking and releasing levers 15 and 16 for connecting said brim-forming die to cause it to descend in advance of said crown-forming die but to permit said crown-forming die to afterward descend independently thereof.

4. In a hat-forming machine, the combination 30 of lower brim and crown forming dies, an upper brim-forming die having an opening for the crown, a top crown-forming die and a plurality of side-shaping members pivotally carried around said top forming-die, 35 said members having overlapping edges with rounded corners, each member having an outer bearing and operating-surface adapted to coact with the sides of the opening in said brim-forming die.

40 5. In a hat-forming machine, the combination of lower brim and crown forming dies, an upper brim-forming die having an opening for the crown, a top crown-forming die and a plurality of side-shaping members 45 pivotally carried around said top forming-die, said members having overlapping edges, each of said members having an inner shaping-surface, a lower shaping-surface and an outer shaping-surface.

50 6. In a hat-forming machine, the combination of a bed, lower brim and crown forming dies supported thereby, a cross-frame, operating-rods therefor, a top crown-forming die carried by said cross-frame, an upper brim-forming die also carried by said cross-frame, a plurality of movable side-shaping members carried around said top forming-die and means of connection between said brim-forming die and said crown-forming dies for 55 causing said upper brim-forming die to descend in advance of said crown-forming die and to ascend in reverse order, substantially as described.

60 7. In a hat-forming machine, the combination of lower brim and crown forming dies,

an upper brim-forming die having an opening for the crown and a plurality of movable side-shaping members each having overlapping edges inclined to each other with rounded inner corners each member having 70 an inner shaping-surface adapted to be brought into operation, substantially as described.

8. In a hat-forming machine, the combination of lower brim and crown forming dies, 75 an upper brim-forming die having an opening for the crown and a plurality of movable side-shaping members having overlapping edges inclined to each other with rounded inner corners each member having an inner 80 shaping-surface and a lower shaping-surface adapted to be brought into operation, substantially as described.

9. In a hat-forming machine, the combination 85 of lower brim and crown forming dies having an annular groove between the crown and brim forming portions, an upper brim-forming die having an opening for the crown and a plurality of side-shaping members having overlapping edges each of said members 90 having an inner shaping-surface and an outer shaping surface adapted to be brought into operation, substantially as described.

10. In a hat-forming machine, the combination 95 of a lower brim-forming die having an upwardly-curved and flared surface, a lower crown-forming means leaving an annular groove at the base of the brim-forming die, an upper brim-forming die having an opening for the crown and corresponding to a portion 100 of said lower brim-forming die and a plurality of movable side-shaping members having inner, lower and outer shaping-surfaces and means for bringing said dies and shaping members into operation for the purpose specified. 105

11. In a machine for forming hats and the like, the combination of a crown-forming die, a plurality of movable outer crown-forming members having overlapping, inclined inner 110 edges in the shaping-surfaces, alternate members being arranged to close inside of the adjacent members and having tapering shaping-surfaces considerably wider near the bottom than at the top, and means for bringing 115 said members into operation.

12. In a machine for forming hats and the like, the combination of an inner crown-forming die, a plurality of movable outer crown-forming members having overlapping 120 edges with inclined inner shaping-surfaces and also having lower shaping-surfaces, the alternate members having rounded lower corners, above the lower shaping-surfaces and means for bringing said members into operation. 125

13. In a hat-forming machine, the combination of inner crown-forming dies, and two sets of movable outer crown-forming members, each member of one set having a re- 130

cess at each end cut back from its shaping-surface to receive a portion of the adjacent member of the other set, the edge of the recess which lies in the shaping-surface being inclined throughout a portion of its extent and terminating in a curve, the opposite edges of each of the members of the other set being inclined relative to each other for a portion of their extent and terminating in rounded lower corners and corresponding to the recesses substantially as described.

14. In a hat-forming machine, the combination of upper and lower brim-forming dies, inner and outer sets of crown-forming members, one of said sets of members being movable vertically and laterally relative to the other set, and one of said brim-forming dies being movable vertically, means for simultaneously operating one of said brim-forming dies and said movable set of crown-forming members, with the brim-forming die in advance of the crown-forming members, and means for disconnecting the brim-forming die to permit the crown-forming members to move independently.

15. In a hat-die, a plurality of outer crown-shaping members arranged in two sets movable toward and from each other and having inner shaping-surfaces, the members of one set being arranged to swing outside of the other set and having recesses at the inner sides, and the members of the other set being arranged to fit in said recesses and being wider at the lower edges in the shaping-surface than the members of the outer set at the lower edges in the shaping-surface.

16. In a hat-forming machine, the combination of inner crown-forming dies and two sets of movable outer crown-forming members, each member of one set having a recess at each end cut back from its shaping-surface to receive a portion of the adjacent mem-

ber of the other set, the edge of the recess which lies in the shaping-surface being inclined throughout a portion of its extent, the opposite edges of each of the members of the other set being inclined relative to each other for a portion of their extent and corresponding to the recesses substantially as described.

17. In a hat-machine, lower brim and crown forming dies, an upper brim-forming die having an opening, and a plurality of pivoted outer crown-forming members vertically movable through said opening and constantly overlapping at their adjacent edges and engaging one another during the entire contracting period.

18. In a hat-machine, lower brim and crown forming dies, an upper brim-engaging die having an opening for the crown, a plurality of relatively movable outer crown-forming members, a vertically-movable press supporting said upper brim-die and said outer crown-forming members, and lever-controlled means for disconnecting said brim-die so as to permit said crown-forming members to descend through said opening.

19. A shaping-machine, including an annular segmental die, the segments of which have overlapping edges and are movable relatively to each other, each segment having inner, lower and outer shaping-surfaces.

20. A shaping-machine, including two upper and two lower dies, and lever-releasable means of connection between said upper dies whereby one of said upper dies positively prevents the other upper die from coming into operation until released.

Signed at New York, N. Y., this 10th day of August, 1904.

CHARLES W. STEVENS.
